UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,215,723.

Specification of Letters Patent. Patented Feb. 13, 1917.

Application filed September 13, 1916. Serial No. 119,803.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My invention relates to typewriting machines and more particularly to a returning spring supporting bar and to means for mounting and adjusting said bar.

The main objects of said invention, generally stated, are to provide simple and 15 efficient means of the character specified which may be manufactured at small cost and enable the parts to be readily assembled and disassembled when desired.

To the above and other ends which will 20 hereinafter appear, my invention consists of the features of construction, arrangements of parts and combinations of devices set forth in the following description and particularly pointed out in the appended 25 claims.

In the drawings wherein like reference characters indicate corresponding parts in the different views,

Figure 1 is a fragmentary vertical fore 30 and aft sectional view showing only so much of a typewriting machine as is necessary to illustrate my invention.

Fig. 2 is a transverse sectional view of the same taken on the line $\alpha-\alpha$ of Fig. 1 35 and looking in the direction of the arrow at said line.

In the present embodiment of my invention a system of key levers for the type actions, etc., constitute the actuating members 40 to which the returning springs are applied. It will be understood, however, that the invention may be employed wherever found available and that the character of the actuating members to which the returning 45 springs are attached is immaterial.

The frame of the machine comprises a base 1 in which is suitably supported, in a manner not shown, a fulcrum bar or rod 2 for the actuating members, which in the 50 present instance comprises a series of key

levers 3. These levers, as shown, extend fore and aft of the machine in parallel arrangement, each key lever being connected to a contractile returning spring 4. The upper ends of these springs are connected to a hollow supporting bar which is curved in cross section and is designated as a whole by the reference numeral 5. This bar is preferably made of sheet metal and is struck up into tubular or substantially oval or 60 C-shaped formation in cross section. The bar extends transversely across the machine and is perforated near the ends and at the under side thereof to receive the cylindrical reduced ends 6 of the set screws 7. These 65 screws work in tapped openings in the base of the machine for vertical adjustment. By reducing the ends 6 of these screws shoulders 8 are provided thereon for co-operation with the body portion of the supporting bar 70 5 at the under side thereof. It will be understood, therefore, that the bar is supported only at the ends thereof and that an adjustment of the screws 7 is effective to give a bodily adjustment of the supporting bar 75 5, raising or lowering the latter to effect a simultaneous adjustment of the force of all of the contractile springs 4 connected to said bar. When the screws are forced upwardly the bar 5 is raised and more tension put 80 into the springs. When the screws are turned downwardly the bar is caused to follow by the action of the gang of springs and at the same time the tension of the springs is lessened.

One edge of the sheet metal plate from which the supporting bar is formed is slotted transversely at 9 to form a series of projections, hooks or tines 10. When the bar is formed as shown these tines partake 90 of the curvature of the bar and are contained within the outline thereof and constitute hook-like members over each of which a loop 11 at the upper end of the associated returning spring may be hooked 95 in order to detachably connect the springs to the supporting bar. A slight space 12 is provided between the end of each hook-like projection 10 and the opposite edge 13 of the supporting bar to facilitate engage- 100

ment or disengagement between the upper looped ends of the springs and the hooks 10 on the supporting bar.

Upwardly extending lugs 14 project from 5 the base of the machine at each side thereof. Each of these lugs has an open-mouthed or open-ended slot or recess 15 to provide forks or ways in which the supporting bar may be seated and guided in its adjustment by 10 the screws 7.

It will be understood that the force of 15 the springs 4 maintains the supporting bar seated on the shouldered ends of the screws 7, which extend through tapped openings in 20 the bottom wall of the slots 15. The bar is prevented from moving fore and aft of the machine and from turning by the forks or ways in which it is seated and the reduced ends 6 of the screws taking into the apertures in the bar prevent an axial or endwise movement of the bar. The springs also assist in keeping the bar in proper working position.

In assembling the parts it is merely necessary to introduce the supporting bar in place 25 by dropping or moving it transversely of itself through the open ends of the slots 15 into its bearings or ways and seating it on the reduced ends of the adjusting screws. 30 Previous to this, if desired, the upper ends of the springs 4 may all be connected to the hooks 10. Thereafter the lower ends of the springs may be hooked into the holes 16 in the key levers. Of course, though, if desired, 35 the springs may first be attached to the key levers and subsequently attached to the hooks on the bar. When the returning springs are detached the supporting bar may be readily removed by merely lifting it from 40 its position in the open-mouthed ways or slots in the base of the machine.

Various changes may be made in the construction, depending on the character of the machine in which it is employed and the 45 character of the actuating devices or members to which the returning springs are attached, the construction shown and described merely representing one form of embodiment of my invention.

50 What I claim as new and desire to secure by Letters Patent, is:—

1. In a typewriting machine, the combination of an oval-shaped hollow supporting bar provided with tongues, ways in which the ends of the bar are slidably mounted, 55 means for effecting a bodily adjustment of the bar in said ways, and springs each connected at one end to one of said tongues.

2. In a typewriting machine, the combination of a hollow supporting bar which is substantially C-shaped in cross-section and is provided with a series of engaging tines along one edge and within the outline of 60 said bar, key actuated members, and con-

tractile returning springs each having one end hooked over one of said tines and connected at its opposite end to one of said key actuated members.

3. In a typewriting machine, the combination of a machine frame provided with 70 slotted bearings or ways, a hollow sheet metal supporting bar provided with engaging tines and mounted at its ends for bodily adjustment in said ways, the end portions of the bar having each a greater dimension 75 longitudinally of its slotted bearing than transversely thereof, whereby a turning movement of the bar in its bearings is prevented without interfering with said bodily adjustments, and springs connected to said 80 tines.

4. In a typewriting machine, the combination of a machine frame having open-ended slots formed therein, a supporting bar received and guided in said slots and 85 adapted to be inserted in or removed therefrom through the open ends of the slots, set screws which extend through tapped openings in the bottom walls of the slots and bear at their end portions against the supporting bar to effect an adjustment thereof 90 in the slots, and returning springs connected to said bar.

5. In a typewriting machine, the combination of a machine frame having an upwardly extending lug on each side of the 95 base thereof, said lugs being slotted to form ways; a supporting bar received and guided in said slots; means for effecting a bodily adjustment of the bar in said slots; and returning springs connected to said bar.

6. In a typewriting machine, the combination of a machine frame having an upwardly extending lug on each side of the 105 base thereof, said lugs being slotted to form ways; a supporting bar received and guided in said slots; set screws which extend through tapped openings in the bottom walls of the slots and bear against the supporting bar to effect an adjustment thereof in the 110 slots; and returning springs connected to said bar.

7. In a typewriting machine, the combination of a machine frame which has an upwardly extending lug on each side of the 115 base thereof, said lugs being slotted to form ways; a tubular sheet metal supporting bar received and guided in said slots and having an aperture in each end portion thereof; an adjusting screw threaded into the bottom wall of each slot and having a reduced end that forms a shoulder, the reduced end of each screw being received in an aperture of the bar, and the shoulder of each screw bearing against the body of the bar; and returning springs connected to said bar.

8. In a typewriting machine, the combination of a machine frame provided with

ways, a hollow sheet metal supporting bar which is substantially C-shaped in cross-section and is slotted transversely thereof to form a series of teeth, adjustable means for effecting a bodily adjustment of said bar in said ways, a series of key actuated members, and a series of returning springs therefor, each spring at one end being hooked over a tooth on the bar and at its

opposite end connected with a key actuated member.

Signed at Ilion, in the county of Herkimer and State of New York, this 11th day of September, A. D. 1916.

GEORGE A. SEIB.
